UNITED STATES PATENT OFFICE.

JOHN ARTHUR BLAKE AND JAY KENRICH, OF WOLCOTT, INDIANA.

CONCRETE-BLOCK MACHINE.

No. 809,901.

Specification of Letters Patent.

Patented Jan. 9, 1906.

Application filed April 3, 1905. Serial No. 253,394.

To all whom it may concern:

Be it known that we, JOHN ARTHUR BLAKE and JAY KENRICH, citizens of the United States, and residents of Wolcott, in the county of White and State of Indiana, have made certain new and useful Improvements in Concrete-Block Machines, of which the following is a specification.

This invention is an improvement in machines for use in making concrete building-blocks; and the invention consists in certain novel constructions and combinations of parts, as will be hereinafter described and claimed.

In the drawings, Figure 1 is a top plan view of a machine embodying our invention. Fig. 2 is a detail side elevation of the mold-box taken from the inner side thereof, the inner side section and the end sections being opened. Fig. 3 is a side elevation of a machine, partly in section; and Fig. 4 is an end elevation of the box, the sides and ends being open. Fig. 5 is a detail top plan view, partly in section, showing one of the mold-boxes and the latch for securing the same in pressing position. Fig. 6 is a cross-sectional view of the bottom of the mold-box. Fig. 7 is a detail top plan view of a portion of the bottom of the mold-box, the platen being removed; and Fig. 8 is a detail side view of one of the dogs used for supporting the platen after the pressing operation.

In carrying out our invention we employ a revolving carrier for a series of mold-boxes, such carrier being mounted on a base A and comprising an upright shaft B, top beams B' on said shaft B, and strut-braces B², supporting the top beams B', roller-bearings C being provided between the base b of the shaft B and a bed-plate a on the base-beams A, and a tie-rod D extending through the plate a and thence through the shaft B in order to hold the shaft firmly in connection with the base or support, as will be understood from Fig. 3 of the drawings.

The main frame has its base-beams A extended at one end at A' beyond the path of the revolving mold-boxes, and on this extension A' is mounted an upright E, which extends upwardly, as shown, nearly to the top of the mold-boxes F, and is provided at its upper end with a locking-bar E', by which the mold-boxes are secured in position for the action of the presser-heads, presently described. As shown, the locking-bar E' is pivoted at e to the struts G, and is notched in its

free edge to engage with a pin on the outer side of the mold-box, as best shown in Figs. 3 and 5 of the drawings. A strut-beam G is secured at its lower end to one of the base-beams A and at its upper end to the upright E, and is provided between its ends with boxes G' and G², forming guides for the carrying-bars H' and I' of the presser-heads H and I, the former operating from above and the latter operating from below into the mold-boxes for the purpose of pressing the concrete in the mold-boxes, as will be understood from Fig. 3 of the drawings. I also provide one of the base-beams A with boxes h' and h², forming guides for the lower ends of the bars H' and I', so the latter are guided accurately into and out of the mold-box in the operation of the invention. As shown, the carrying-bar H' for the presser-head H extends on a straight line throughout its length, while the carrier I' is provided at its upper end with a forwardly-projecting portion I² to support the presser-head I directly above the mold-box. To operate the presser-heads, we provide a rocking disk J, having a shaft J', to which the handle-lever J² is secured, and this rocker J is connected by links h and i with the carrying-bars of their respective presser-heads, so that as the rocker J is operated the presser-heads will be moved reciprocally and operated into and out of pressing position. As shown, the top beams B' are metal bars diverging from a central block K at the top of the shaft B to a point near their outer ends and having such outer ends b' extending outwardly along the outer sides of the mold-boxes F and secured to the base-frames of the said mold-boxes, as will be understood from Figs. 1 and 3 of the drawings.

The mold-boxes have the open bottom frames F', the inner side sections F², the outer side sections F³, and the end section F⁴. The sections F² and F³ are hinged at f² at their lower edges, so they may turn outwardly, as shown in Fig. 4, and these sections are provided on their inner sides with the longitudinal inwardly-projecting rounded ribs 1, which form the longitudinal channels in the sides of the concrete block when the latter is completed. The end sections F⁴ are also provided on their inner sides with the inwardly-projecting ribs 1, and these end sections F⁴ are hinged at one edge f⁴ to the outer section F² of the mold-box and are provided with locking devices F⁵ for securing the outer side section F³, such locking

devices comprising pivoted bars having on their outer sides near their swinging ends projections f^3 , which interlock with projections f^3 on the outer side section for securing the latter when the mold-box is closed. By the described construction the mold-box may be opened to discharge a pressed block and then closed and secured in condition to receive the loose concrete for forming another block. The side sections F^3 and F^2 are provided with openings 2 and 3, in which operate the transverse core-blocks K , which are preferably round in cross-section and are of such length as to extend when applied to the box entirely across the same, as shown in Fig. 1 of the drawings. These core-blocks K are connected at their inner ends by a cross-bar K' , to which is connected a slide-rod K^2 , passing through a guide L' in a guide-bar L , and a lever M pivots at M' between its ends and connects at M^2 by a sliding connection with the slide-bar K^2 , so it may be operated to throw the core-blocks into the advanced position shown in Fig. 1 or to retract the said blocks so they will clear the mold-box when it is desired to open the latter and remove the pressed block. As shown in Fig. 4, the inner side section F^2 has a limited opening movement, being stopped by a bar N projecting from one of the top beams, and the core-blocks are sufficiently loose in the openings 3 to permit the section F^2 to adjust to the position shown in Fig. 4 when it is desired to remove the pressed block.

After the block has been pressed the core-blocks may be drawn out of the box by means of the lever M , and the locking-bars F^5 may be adjusted to release the outside end doors or sections, and the end doors may be opened, which will cause the inside door or section to tilt away from the press-block. The outside section may now be turned down when the block is free and can be removed from the machine. To close the mold, the empty pallet or platen O should be placed in the bottom of the mold. The latter has a metal plate O' , which will move upward as the lower press-head H rises. This will cause the pallet O to move upwardly past small clutches P , which will hold it until the pressed block is removed, and the doors or sections may be closed and the core-blocks adjusted to the position shown in Fig. 1, and the mold-box is ready for refilling.

Each press-box contains four dogs P , one at each corner, and the plate O' is a loose plate which remains in the base of the press-box and is provided with openings O^2 , in which the points of the dogs P operate, as will be understood from Fig. 6. When the lower press-head comes in contact with the loose plate O' , it elevates the latter, and also the pallet or platen O , the corners O^3 raising the dogs P . When the pressing operation

has been completed, the dogs, the plate O' , and the pallet O assume the position indicated in dotted lines, Fig. 6, the springs P' on the under sides of the dogs pressing against the corners O^3 and forcing the ratcheted surface P^2 into engagement with a corresponding surface on the under side of the pallet O and holding the pallet and dogs in position. When the lower press-head is lowered, the loose plate O' will fall to its original position, as indicated in full lines, Fig. 6, and when the pallet O is removed with the press-block the dogs P will fall to their initial positions, as shown in full lines, Fig. 6, and an empty pallet or platen O may be placed in position when the press-box is ready for another charge of concrete. Any suitable design of top face may be secured by changing the top presser-head I , the latter being preferably removable, as indicated in Fig. 3, so that different designs may be provided.

In operation after the block has been pressed in the position shown in Fig. 3, the lock E' may be released and the revolving carrier turned to bring another mold-box into position between the press-heads, and the pressed block may be removed after the box has been adjusted clear of the press-heads, as will be understood from Figs. 1 and 3 of the drawings.

Having thus described our invention, what we claim as new, and desire to secure by Letters Patent, is—

1. A machine for pressing concrete blocks, comprising a base having its beams extended at one end, an upright mounted on such extension, a strut-bar between said upright and the base and provided with box-loops forming guides for the presser-bars, loops on the base in line with those on the strut-bar, the presser-heads operating one above the other and having their carrier-bars movable longitudinally in the aligned loops of the base and strut-bar, a rocker between said carrier-bars, links connecting said rocker with the carrier-bars, a handle for operating the rocker, a revolving carrier comprising a shaft having a base portion, top beams, a central block from which said top beams diverge, the mold-boxes carried by said top beams and comprising the base-frames, the inner and outer sections hinged at their lower edges and having openings for the core-blocks, the end sections hinged to the side sections, lock devices for holding the box closed, the boxes being movable successively by the turning of the carrier into register with the press-heads, the core-blocks, the slide-bars connected with said blocks, means for operating the blocks, a plate on the base, ball-bearings between said plate and the base of the carrier-shaft and a tie-rod holding said shaft to the base-plate, substantially as and for the purposes set forth.

2. In a machine substantially as described the combination with a revolving carrier having a series of mold-boxes and upper and lower press-heads between which the mold-
5 boxes may be successively presented by the revolution of the carrier, of means for operating the opposite press-heads simultaneously and reciprocally whereby the object may be pressed without being moved out of
10 its plane of movement, core-blocks movable transversely through their respective mold-boxes and means in connection with the revolving carrier for operating their respective core-blocks, substantially as set forth.
- 15 3. The combination of a main frame and series of mold-boxes having hinged sides and ends, a carrier revolving on the main frame and supporting the series of mold-boxes, upper and lower press-heads between which the
20 mold-boxes may be successively presented core-blocks movable through the hinged sides of their respective boxes and means for operating the press-heads reciprocally, substantially as set forth.
- 25 4. The combination with pressing devices and a revolving carrier having a circular series of mold-boxes, of core-blocks movable transversely through their respective mold-boxes and individual operating devices for
30 the several core-blocks, such devices and core-blocks being movable with their respective mold-boxes, substantially as set forth.
- 35 5. The combination with the press-box and its movable bottom plate, of the press-head arranged to operate said bottom plate, a pallet or platen arranged to be lifted by the bottom plate and means for supporting such pallet or platen when raised, substantially as set forth.
- 40 6. The combination in an apparatus, substantially as described, of pressing devices, a revolving carrier having a series of mold-boxes arranged to be presented successively to the pressing devices, core-blocks movable
45 transversely across their respective mold-boxes and means supported by the carrier for operating their respective core-blocks, substantially as set forth.
7. In an apparatus substantially as described, a press-box having a movable bottom plate arranged for operation by the press-head, pivoted dogs engaged by said bottom plate and a pallet or platen arranged to be lifted by the bottom plate and supported in raised position by the dogs.
- 50 8. In an apparatus, substantially as described, a revolving carrier, a series of mold-boxes thereon, core-blocks for each of said boxes and means supported adjacent to the boxes for operating their respective core-blocks, substantially as set forth.
- 55 9. The combination in an apparatus, substantially as described of the upper and lower pressing devices, the press-boxes having a movable bottom plate arranged for operation by the lower pressing devices, a pallet or platen arranged to be lifted by the bottom plate, and dogs arranged for engagement by said bottom plate and adapted to support the pallet or platen in raised position, substantially as set forth.
- 60 10. The combination in an apparatus substantially as described, of a main frame having a base portion and an upright thereon, a strut-bar extending between the base and upright and provided with loops forming guides for the carrier-bars of the press-heads, loops on the base in alignment with those on the strut-bar, the press-heads having their carrier-bars movable in the aligned loops, means for operating said press-heads reciprocally, the mold-boxes and a movable carrier for same, substantially as set forth.
